VENETIAN BLIND

Harold R. Haase, River Forest, Ill.

Application May 31, 1938, Serial No. 211,190

14 Claims. (Cl. 156—17)

This invention relates to Venetian blinds and more particularly to the control head for such blinds. The control head of the blind is that portion of the blind which is supported at the top of the window frame and from which the slats of the blind are suspended. It normally includes both raising cords for raising the slats and tilt means for manipulating the latter tapes by which the slats are normally separated, to tilt the slats.

In recent years the ancient Venetian blind industry has become quite active due to the fact that Venetian blinds have again come into style. One result of such activity has been a great number of different designs for the head structure of the blinds. Because the current simplification or omission of draperies leaves the head structure exposed, it has been found desirable by some manufacturers to conceal the tilt mechanism and in other respects make the head structure as neat as possible. One of the obvious ways of making the head structure neater is to reduce its height as well as to conceal the tilt mechanism therein. To this end an old and obvious expedient was adopted, the thick wooden head rail being replaced by a hollow metal casing which both supports and houses the tilt mechanism and the raising pulleys. Such metallic support casings, however, had the disadvantage that they had to be especially made for each blind and required expensive machinery for their manufacture. An object of the present invention is therefore to provide a satisfactory concealed-tilt head structure in which the relatively expensive and inconvenient metal casing is not required. Expressed differently, an object of the invention is to provide a construction which utilizes the old conventional wood head bar with fittings which can easily be applied thereto even in small shops but which do not increase the overall height of the head structure as compared to satisfactory metal casings.

Once a manufacturer decided to adopt a metal support casing he could merely select one of the known tilt structures to go within the casing or he could design a new one which would permit him to reduce the height of the casing. The chief difficulty in reducing the height of the casing was the necessity of providing adequate vertical movement of the tilt tapes and the desirability, for neatness, of having the tilt tapes extend into the casing at all times, as it had in built-up wooden casings. In general, it is necessary for each of these tapes to move up and down a distance approximately equal to the width of the slats, this distance being the distance that the

edge of the slat moves as it is tilted from a nearly vertical position in one direction to a nearly vertical position in the other direction.

In a preceding construction I introduced a new principle into the art of reducing the height of the tilt mechanism, namely the principle of forming a loop in the tape as it was raised so that the take-up of the tape was twice the height of the loop and hence could be nearly twice the height of the head structure. According to the present invention no loop is formed initially but the tape is moved approximately the height of the casing and then drawn up still further by being carried inwardly and downwardly over a roller. The very simple mechanism is so compact in a vertical direction that it may be positioned above a wooden head rail of conventional thickness, the two together having a height which, being only equal to the width of the individual slats, is entirely satisfactory.

In general, the illustrated form of the invention includes two separate tilt units, each of which can be secured on the top of a Venetian blind head rail. The tilt cord pulley with its worm gear and the raising cord pulley and lock are also separate units so that they can be secured to the wooden head rail. Thus, the two tilt units and the worm wheel and pulley unit, together with cord pulleys and cord brake if desired, may be furnished to the small blind producer so that he can make up his head structures from the wood stock that has commonly been used for head rails of Venetian blinds. The height of the composite structure is such that an ordinary Venetian blind slat may be applied to the front of the head rail and completely conceal the mechanism thereabove. The slight amount of cutting or routing out of the head rail which is necessary can easily be performed by anyone who has previously been equipped to manufacture Venetian blinds of the exposed tilt type.

Additional objects and advantages of the invention will be apparent from the following description and from the drawing, in which:

Fig. 1 is a front view of the control head chosen for illustration of this invention with the face slat removed for the sake of clarity.

Fig. 2 is a top view of the structure shown in Fig. 1 with the face slat in place.

Fig. 3 is a sectional view taken approximately on the line 3—3 of Fig. 2, showing the tapes in one extreme position.

Fig. 4 is a sectional view taken approximately on the line 4—4 of Fig. 2 and showing a preferred construction of tilt worm and pulley mechanism.

Fig. 5 is an end view taken on the line 5—5 of Fig. 2 and showing in dotted lines the position and manner of securing the pulley and cord lock mechanism.

5 Although this invention may take numerous forms, only one has been chosen for illustration. In this form the blind except for its head construction may be regarded as conventional including the conventional slats 11 and bottom rail 12 which are suspended in uniformly spaced positions by ladder tapes 13 which are so named because each includes the front tape to which the number 13 is applied, the back tape 13', and cross tapes 14 as seen in Fig. 3. If the front tapes 13 are raised and the back tapes 13' are lowered, the slats 11 will be tilted in one direction, while if the tapes are reversed the slats 11 will likewise be reversed. The slats and the head rail may be drawn upwardly by a raising cord 16 which is secured at its ends to the bottom rail 12 and extends up over pulleys 17, down around pulley 18 to form a loop 19 which is grasped with the hand to raise or lower the blind. The slats may be retained in a raised position by an automatic lock 21 which may be of any form desired.

10 The head structure includes the pulleys 17 and 18 and the cord lock 21, all of which may be considered conventional and all of which are carried by a head rail 23 which has the advantage of being conventional in its general nature. In other words, it is a wood rail made of the same stock from which conventional head rails are made and having a slot 24, seen best in Fig. 5, extending along its top for the reception of the raising cord 16. The pulleys 17 and 18 may be of conventional size instead of having to be reduced in size as has been the case with some metal heads in order to make sufficient room for the tilting mechanism thereabove.

40 *Tilt mechanism*

45 The tilting mechanism includes a pair of identical units each including a U-shaped bracket 26, a pair of rollers (or fixed guide bars) 27, and a sprocket 28. The rollers 27 are carried by the upwardly extending legs of the U-shaped bracket 26 and may rotate either on studs formed on their ends or on a separate pivot pin extending therethrough. The sprocket 28 is carried by a rod 29 which extends through both of the brackets 26 and also extends into a worm gear 31. The rod 29 is noncircular in shape, and the worm gear 31 and sprockets 28 are internally shaped to fit the rod 29 so that the rod 29 may be turned by the worm gear 31 and will rotate the sprockets 28. A hexagonal shape is preferred for the rod 29 because it may be obtained readily, being a stock item. It extends through round holes in the vertical legs of brackets 26, at least one hole in each bracket fitting the rod 29 fairly closely so as to act as a journal therefor. The sprocket 28 may be centered between the legs of the bracket 26 in any suitable manner, one of the simplest ways being that illustrated in which extensions 33 are bent 60 over from the tops of the legs of bracket 26 and then bent downwardly again and bifurcated as seen in dotted lines at 34 in Fig. 3. The downwardly extending and bifurcated ends of the extensions 33 will lie adjacent opposite faces of the 65 sprocket 28.

70 A chain 36 extends under the sprocket 28 and in mesh therewith and passes over both of the rollers 27 as seen in Figs. 2 and 3. At each end of the chain 36 is pivoted a coupled 37 which, as seen 75 best in Fig. 3, includes a doubled-over toothed

strip 38 which engages the top of one of the ladder tapes 13 or 13' to which it is firmly secured by its teeth. The strip 38 has an upward extension 39 at its center which is pivotally connected to the chain 36 so that the coupler 37 with the tape 5 secured thereto may be drawn over the roller 27 to the position shown at the left in Fig. 3.

10 The two extreme positions for the tapes 13 and 13' are seen in Fig. 3. The tape 13 is in its lowermost position with the coupler 37 adjacent the bottom of the head rail 23. The tape 13', on the other hand, extends up over the roller 27 and downwardly in a direction tangent to the sprocket 28 with its coupler 37 approximately in contact therewith. It is thus seen that the movement of 15 each tape is at least equal to or may be even greater than the outside height of the head structure including both the head rail 23 and the brackets 26. If still greater movement were necessary, holes could be provided in the coupler 37 20 and even in the top of the tapes 13 and 13' so that these could be drawn under the sprocket 28. It is not believed, however, that this will ever be necessary because, if the head structure is as high and as wide as the slats 11, the relative extent of 25 movement illustrated in Fig. 3 will be enough.

20 To prevent any possibility of entanglement of the chain 36 guide plates 41 are bent upwardly from the base 42 of the U-shaped brackets 26. A portion of the metal cut out from adjacent the 30 plate 41 and the base 42 at each corner may be bent outwardly to form the securing lugs 43 to facilitate securing the bracket 26 to the head rail 23 by screws as seen clearly in Fig. 2.

30 In order to permit the couplers 37 to move up 35 and down within the lateral outlines of the head rail 23, the head rail is cut or routed out to form channels 46. A hole is also drilled through the head rail 23 at this point to receive the pin 47 for holding the pulley 17.

40 Although the rod 29 could be turned in some other manner than by the worm gear 31, a worm gear is desirable because of its self-locking co-action with the driving worm 48. In other words, when the slats have been tilted to any position 45 they will stay in that position until the worm 48 is manually turned. The worm 48 is driven by a tilt cord 49 which extends around a pulley 51 which is preferably serrated at the bottom of its groove and may be provided with spring guards 52 50 which insure an adequate bite between the serrations of the pulley 51 and the cord 49 to prevent the cord 49 from slipping or creeping on the pulley 51.

55 The pulley 51 and the worm 48 are of course 55 keyed to or otherwise rigidly carried by a common shaft which is rotatably carried by a bracket 54 in which the rod 29 is also journaled. The worm gear 31 is mounted on the rod 29 and is maintained in a predetermined longitudinal position 60 by guide portions 61 of the bracket 54. The bracket 54 is secured by suitable screws to the head rail 23 as seen best in Fig. 2. The spring guards 52 are secured to the bracket 54 at their lower ends.

65 As will be seen from Fig. 4, the illustrated construction of worm and pulley unit requires that the head rail 23 be routed out to form a recess 63 for receiving the bracket, as well as a passage 64 for receiving the tilt cords 49. This is not 70 objectionable from the standpoint of weakening the head rail 23 since the pulley and worm unit is always positioned quite close to the end of the head rail 23 where the full cross-sectional strength of the head rail is not needed. At the 75

positions of the brackets 26 where somewhat greater head rail strength is desired, an adequate strength is maintained since the channels or passages 46 leave relatively heavy portions of 5 the head rail substantially intact from top to bottom.

The only additional routing out of the head rail that is necessary is near the other end of the head rail for the pulley 18 and cord lock 21, both 10 of which are carried by the same bracket 66 secured in place by a screw passing through a lug 67 formed on the bracket 66. The bracket 66 is preferably positioned at an angle as seen in Fig. 5 so as to carry the raising cord 16 from its position 15 in the longitudinal groove 24 over approximately to the edge of the head rail 23. The hole for the bracket 26 will of course be inclined as is the bracket so that there will not be any unnecessary weakening of the head rail.

10 Since one object of putting the tilt mechanism above the head rail 23 is to permit its concealment, it is obvious that a face board 69 should be secured on the front side of the head rail 23. One of the advantages of the present invention is that 15 the entire head structure is sufficiently low in total height so that the face board 69 may be made from ordinary Venetian blind slat stock, which of course every Venetian blind manufacturer has on hand. This face slat 69 may be 20 tacked to the head rail 23 or secured thereto by concealed securing means between it and the head rail or simply secured in place by the supporting brackets (not shown) at the ends of the rail 23. One preferred form of securing means 25 has been illustrated, being seen best in Fig. 5. Here two or more spring steel clips 71 are nailed to the head rail 23 and are so designed that the face slat 69 may be inserted therein or removed therefrom with ease. The method of inserting 30 the face slat is to insert its upper edge first, whereupon the clips 71 will flex sufficiently to permit the lower edge of the slat to be snapped into place. The face slat 69 does not support any portion of the weight of the apparatus and may 35 therefore be attached to the head rail 23 relatively loosely. In fact, it is preferred that it be secured only near its ends so that if there is any slight sagging of the head rail 23 this will not produce a pull on the securing means for the face 40 slat 69. Of course, such sagging will never be great inasmuch as one or more intermediate brackets will be provided for holding up the center of head rail 23 when its length is such as to make such brackets necessary.

From the foregoing it is seen that a Venetian blind control head has been provided which can readily be manufactured in any required size by a manufacturer or small shop keeper who has a supply of the fittings in stock and which will 5 nevertheless be as satisfactory in appearance as the control heads which in the past were built into metal casings and therefore required expensive machinery for their production. It is merely necessary for the manufacturer or small 10 shop keeper to take a conventional head rail of the proper length having a longitudinal groove 24 therein, install the pulleys 17, the pulley 18 and cord lock 21 in the usual manner, rout out the recess 63 and the slots 46, and apply the proper fittings adjacent thereto. When the ladder tapes have been cut to the right length, the chains 36 with the couplers 37 thereon may be 15 attached to the top thereof with the ladder tapes slipped into the slots 46 and the chains passing over the rollers 27. The sprockets 28 are next

inserted between the bracket extension 33, and the rod 29 may then be threaded through the worm gear 31 and sprockets 28. The head is now complete and the raising cord 16 and tilt cord 49 may be applied thereto if this has not been done previously, the slats may be inserted in the tapes and the cords threaded through the slats and secured to the bottom rail 12 or otherwise strung in the usual manner. The face slat 69 may be applied immediately but more commonly 5 will not be applied until after the control head has been installed in a window. Although the construction is such that access to the control head should never be necessary until the cord 16 wears out, access when required may be obtained very easily by merely removing the face slat 69 without removing the control head from the window. The control head is so designed that the face slat 69 may be of a height equal to the 10 width of conventional blind slats so that its appearance is satisfactory and no special material is required. In spite of the low height of the head, the movement of the tapes by the tilt mechanism therein is adequate, being greater than the total height of the head. It should be noted that in the preferred form the sprocket 28 is so close to bottom web 42 that the doubled-over strip 38, which lies outside of a tooth on sprocket 28, can not pass between the sprocket and the web 42. This serves to desirably limit 15 the movement of the parts.

The disclosures of this application are illustrative and the invention is not to be limited by them. In fact, if modifications or improvements 20 are not at once obvious, they may be devised in the course of time to make additional use of the broad ideas taught and covered by this application. For example, other elements such as a cable and pulley could be substituted for the chain and sprocket, or if the rollers 27 were urged against 25 a drive roller by springs the tapes could be spliced and driven by them directly. Likewise, the chain need not be taken under the sprocket when its movement to the top of the sprocket would be sufficient. Also, a spliced tape could be slid 30 along a semicircular shoe across the top by pivoted arms.

I claim:

1. A tilt control unit for Venetian blinds including a bracket adapted to be secured above a head rail and having guide means near the upper outer corners thereof, a sprocket between the guide means, and a chain adapted to pass over the guide means and under the sprocket in engagement therewith and having couplers at its 55 ends for securing a ladder tape thereto.

2. A control head for Venetian blinds including a wooden head rail having vertical slots along opposite sides thereof for the passage of ladder tapes therethrough, a bracket positioned above the slots 60 and including guide means positioned over the slots near the top of the bracket, a sprocket positioned generally between the guide means, and a chain extending over the guide means and downwardly under the sprocket in engagement therewith and connected to ladder tapes extending through the slots.

3. A control head for Venetian blinds including a wooden head rail having vertical slots along opposite sides thereof for the passage of ladder 70 tapes therethrough, a bracket positioned over the slots and including guide means positioned near the top of the bracket over the slots, a sprocket positioned generally between the guide means, and a chain extending over the guide 75

- means and under the sprocket in engagement therewith and connected to ladder tapes extending through the slots, said control head being approximately as small in total height as the width 5 of an ordinary blind slat and having a face member formed of blind slat stock secured thereto and hiding said bracket.
4. A tilt unit for Venetian blind control heads including a bracket, guide means secured near 10 the upper outer corners of the bracket, a sprocket positioned intermediate the guide means, and means adapted to be associated with ladder tapes extending over the guide means and under the sprocket in engagement therewith for drawing 15 one side of the ladder tape up over one guide means.
5. A tilt unit for Venetian blind control heads including a bracket, guide means secured near 20 the upper outer corners of the bracket, a sprocket positioned intermediate the guide means, means adapted to be associated with ladder tapes extending over the guide means and under the sprocket in engagement therewith for drawing one side of the ladder tape up over one guide 25 means, and extensions for said bracket extending in juxtaposition with the sprocket for centering it with respect thereto.
6. A tilt unit for Venetian blind control heads including a bracket, guide means secured near 30 the upper outer corners of the bracket, a sprocket positioned intermediate the guide means, and means adapted to be associated with ladder tapes extending over the guide means and under the sprocket in engagement therewith for drawing 35 one side of the ladder tape up over one guide means, said sprocket being positioned on a non-circular rod extending through the bracket and adapted to be rotated by a tilt control device.
7. A tilt unit for Venetian blind control heads 40 including a bracket, guide means secured near the upper outer corners of the bracket, a sprocket positioned intermediate the guide means, and means adapted to be associated with ladder tapes extending over the guide means and under the sprocket in engagement therewith for drawing 45 one side of the ladder tape up over one guide means, said bracket including extensions extending into juxtaposition with the guide means and sprocket for preventing entanglement of the tape-actuating means passing therebetween.
8. A Venetian blind control head including 50 fixed guide means near an upper outer corner of the control head, and means for drawing a ladder tape from a lower corner of the control head up over the fixed guide means and away 55 therefrom at an angle to its approach thereto to move the tape further than its range of movement along a vertical side of the control head.
9. Tilt mechanism for a Venetian blind including fixed guide means at opposite sides thereof, slat control means extending over said guide 60 means, and manipulating means for drawing the slat control means over one guide means and downwardly therefrom while letting it pay out from the other guide means.
- 65 10. Tilt mechanism for a Venetian blind including fixed guide means at opposite sides thereof, slat control means extending over said guide

means, and manipulating means for depressing the slat control means between the guide means and drawing the slat control means over and around one guide means and away therefrom while letting it pay out from the other guide 5 means.

11. A control head for a Venetian blind, including a wooden head rail having a groove along its top to receive raising cords and having pulleys around which the raising cords pass and 10 having apertures through which the raising cords extend downwardly through the head rail, tilt mechanism carried by the head rail on the upper side thereof extending above the head rail a distance less than the thickness of the head rail, 15 and including means for supporting slat control means extending downwardly from the head rail and for operating said slat control means by moving said slat control means up and down a distance greater than the entire height of the control head, and a face member positioned substantially entirely above the bottom of the head rail and concealing said tilt mechanism.

12. A control head for a Venetian blind, including a wooden head rail having a groove along 25 its top to receive raising cords and having pulleys around which the raising cords pass and having apertures through which the raising cords extend downwardly through the head rail, tilt mechanism carried by the head rail on the upper 30 side thereof extending above the head rail a distance less than the thickness of the head rail, and including means for supporting slat control means extending downwardly from the head rail and for operating said slat control means by 35 moving said slat control means up and down a distance greater than the entire height of the control head, clips secured to the head rail, and a face slat removably held within the clips.

13. A tilt control unit for Venetian blinds, including a bracket, a sprocket rotatably carried by the bracket, a chain driven by the sprocket, a coupler associated with the chain and adapted to engage slat control means and having a portion which will rest against the end of a tooth 45 of the sprocket and extend therebeyond as it is drawn against the sprocket by rotation thereof, and fixed means associated with the bracket and lying sufficiently close to the portion of the sprocket with which the chain is in engagement 50 to prevent passage of said coupler between said sprocket and said fixed means.

14. A Venetian blind of the general type including a plurality of slats normally supported in spaced relation by slat control means, means 55 for manipulating the slat control means to tilt the slats, and means for raising the slats, characterized by the use of a wooden head rail for supporting the blind slats, having a passage for the slat control means formed by a shallow open slot in the side of the head rail, and by the use 60 of tilt units supported on the top of the head rail for drawing the slat control means through the slots, and a face member secured to the head rail forming a wall for the slot and concealing 65 the slots and the tilt units.
